UNITED STATES PATENT OFFICE.

SAMUEL E. MAXWELL, OF AVALON, PENNSYLVANIA.

GARAGE-HEATER.

1,372,713.

Specification of Letters Patent. Patented Mar. 29, 1921.

Application filed July 12, 1918. Serial No. 244,543.

To all whom it may concern:

Be it known that I, SAMUEL E. MAXWELL, a citizen of the United States, residing at Avalon, in the county of Allegheny and State of Pennsylvania, have invented a new and useful Improvement in Garage-Heaters, of which improvement the following is a specification.

My invention relates to gas heaters for garages and like places, where absolute safety is required.

The object of my invention is to produce a garage heater which can be used in garages without the least danger of ignition or explosion.

I accomplish this object by means of the device hereinafter more specifically described; reference being had to the accompanying drawings, forming part hereof, in which—

Figure 1 is a front perspective view of my improved heater.

Fig. 2 is a rear perspective view.

Fig. 3 is a partial transverse vertical section taken on line 3—3 of Fig. 2.

Referring to said drawings, 1 is a casing made of light sheet steel or iron. The said casing is provided with an opening 2, at each end and with an opening 2 at the front near the top thereof. The said openings are closed with metallic gauze or fine mesh 3. The bottom of the heater is also provided with an opening, 4, for the purpose of admitting air, which in its upward passage, impinges upon the baffle plate, 5, secured to the front plate of the frame and extends toward the back and terminates a short distance in front of and below the

burner, 6, which is secured in the under walls of the frame and extends lengthwise 40 thereof. The said burner is connected to the gas supply pipe, 7, which is provided with a cock, 8, to control the admission and regulation of the gas thereto. A baffle plate, 9, is located above the burner to direct 45 the products of combustion indirectly toward the exit flue, 10, which may be controlled by a damper. The said heater is provided with hoods, 12, at the front and at both ends, for the purpose of deflecting 50 the heat from the openings, 2, downward. The heater is completely closed, the only openings therein being those closed and protected by the fine mesh. Thus danger from ignition or explosion is entirely avoided. 55

Having described my invention, what I claim and desire to secure by Letters Patent, is—

A garage heater, comprising a frame, open at the bottom and having openings at the 60 front and sides protected by fine metallic mesh, a burner located in said frame, a plate arranged below said burner, the forward end of said plate forming with the front of the frame a narrow passage for directing 65 air toward the burner and hoods arranged above the openings in the sides and front for the purpose of deflecting the heat toward the floor.

In testimony whereof, I have hereunto 70 signed my name in the presence of two subscribing witnesses.

SAMUEL E. MAXWELL.

In the presence of—

JOHN H. RONEY,
ALEX. S. MALON.
